UNITED STATES PATENT OFFICE.

MAYER R. MAIMIN, OF NEW YORK, N. Y., ASSIGNOR TO H. MAIMIN COMPANY,
INCORPORATED, OF NEW YORK, N. Y., A CORPORATION OF NEW YORK.

CLOTH-CUTTING MACHINE.

1,103,791.

Specification of Letters Patent. Patented July 14, 1914.

Application filed December 31, 1913. Serial No. 809,644.

To all whom it may concern:

Be it known that I, MAYER R. MAIMIN, a citizen of the United States, residing in the city of New York, State of New York, have 5 invented certain new and useful Improvements in Cloth-Cutting Machines, of which the following is a full, clear, and exact description, reference being had to the accompanying drawings, forming a part of this 10 specification.

My invention relates to cloth cutting machines of that type comprising a carriage including a supporting base plate, adapted to be propelled manually, and whereon is 15 mounted a motor or other source of power, a power-driven circular or disk-shaped blade, and a blade-sharpening device so mounted that it may be moved into and out of operative position relatively to the circular blade. 20 In the operation of such a machine several layers of cloth are cut simultaneously, the top layer being usually marked with a chalk line to decide the direction and line of the cutting to be done. In so doing the common 25 practice is for the operator to push the carriage toward the work to be cut, by employing one of his hands, acting on the grasping handle of the machine, while his other hand is employed in holding the layers of cloth in 30 proper position to be cut; in consequence the line of cutting is frequently irregular and contact of the workman's hand with the rapidly rotating blade frequently results from accident or inadvertence.

35 The object of my invention is to remedy both of these defects; and my improvements in a machine of the type stated consist of elements in combination therewith adapted to effect the two objects stated, as hereinafter 40 described.

The circular-blade cloth-cutting machine illustrated in the drawings, in so far as it consists of the combined movable base plate and carriage, with the superposed motor and 45 propelling handle, the revolute circular blade, the sharpening device and means to mount it on the carriage in such manner that it may be brought into operative and inoperative positions relatively to the blade, is of a 50 type long well known in the art. It has also been well known to apply to such machines, various means constituting a protecting guard to prevent accidental contact of the operator's hand with the blade; and it is ob- 55 vious that such means must be normally in

front of the knife edge and also capable of being moved from that position in order to enable the sharpening device to be brought into like position when it is desired to grind the edge of the blade. In such known machines, the grinding device consists of a pair of emery or corundum disks mounted in spaced relation, revolubly, on a shaft having its bearings in a bracket which is pivoted on the carriage frame above the plane of the 60 blade and adapted to swing the sharpening disks upward and out of the plane of movement of the blade, this being their normal position wherein their carrying arm is resiliently held by a coiled spring. To sharpen 65 the blade the pivoted bracket is manually swung downward so that the inclined edges of the rapidly rotating blade enter between the separated emery disks, and the latter being freely rotatable on their common bearing 70 one of them grinds one inclined side of the blade in one direction while the other grinds the opposite inclined side of the blade in the reverse direction.

In my novel structural and combined 75 grinding device and guard for the blade, including the pivoted and swinging bracket on which both are mounted, the characteristic features comprise a guard bar which is brought automatically into operative position by the same movement of the pivoted 80 arm which throws the grinding device into inoperative position and vice versa, said movable bracket being so mounted as to have 85 an arc-like movement in front of and in 90 alinement with the plane of rotation of the cutting blade, said movement being manually effected through the operating lever which forms an elemental adjunct of said 95 swinging bracket, and without any connecting links or other interposed actuating means, and the heel of the lever drops automatically into locked position at the terminus of the upward throw of the bracket, thereby holding the guard bar fixedly in 100 perpendicular and operative position in front of and adjacent to the blade edge, as well as at the same time supporting the grinding device in raised and inoperative 105 position. As the guard bar is adjustable vertically in its bearings, the magnifying lens which is rotatably movable can be adjusted in both directions relatively to the work, accordingly.

In the accompanying drawings, illus- 110

trating my invention: Figure 1 is a side elevation, partly broken away, of a cloth cutting machine embodying my invention, showing the sharpening device in the inoperative position, and the blade guard in the operative position. Fig. 2 is a side elevation, showing the sharpening device in the operative position and the blade guard in the inoperative position. Fig. 3 is a front elevation, with the parts in the position shown in Fig. 1. Fig. 4 is a plan, partly in section and partly broken away, showing the parts in the position shown in Fig. 1.

Referring to the drawings, the carriage 15 or frame of the machine comprises, as generally stated, a low base portion or plate 2, a narrow standard 3 rising from the base plate 2 and a motor case 4 supported on the top of the standard 3. A suitable handle 5 is provided which projects rearwardly from the carriage, and by means of which the carriage may be moved by hand over the top of the table supporting the cloth to be cut. The base plate is provided with suitably located anti-friction rollers 6 which are journaled therein in a manner to support the carriage and facilitate its movement over the table.

The standard 3 is provided with a short stud shaft 7 on which is rotatably mounted a sleeve 8 carrying a circular knife or cutter 9. The sleeve 8 has a clamping collar 10 screwed thereon to hold the knife 9 in place and to permit its removal from the sleeve 8. The sleeve 8 and knife 9 thereon are adapted to be rotated in the usual manner by mechanism, not shown, actuated by a motor contained within the case 4.

The lower portion of the knife 9 extends into a slot in the base plate 2 and into a slot in a raised portion of the plate or a block 11 at the lower forward portion of the cutting edge of the blade 9. The block supports that portion of the cloth which is being acted upon by the blade 9 during the cutting operation, the base plate 2 and block 11 moving beneath the cloth and over the top of the table supporting the same in the usual well known manner, during the operation of the machine. The blade 9 and standard 3 are, as usual, made very narrow so that they may readily enter the cut made in the cloth by the blade.

The upper portion of the standard 3 is provided with a forwardly extending arm 12 adjacent to one side of the blade 9. The forward end of the arm 12 carries a pivot stud 13 on which is pivoted a bracket 14, which is so mounted in its bearing as to permit of an arc like reciprocation of it in front of and in alinement with the plane of rotation of the cutting blade. The bracket 14 embraces a pair of emery or corundum sharpening wheels or disks 15 for the blade 9. Each disk 15 is mounted on a shaft 16

which is rotatably mounted in a bearing on the bracket 14, and the disks 15 are spaced a slight distance apart to permit the cutting edge of the blade 9 to enter therebetween. The inner faces of the disks 15 are beveled, 70 as shown, and the shafts 16 are so arranged relatively to the pivot stud 13 and cutting edge of the blade 9 that when the bracket 14 is moved from the position shown in Fig. 1. to the position shown in Fig. 2, the disks 15 75 will be brought into the usual well known operative relation to the cutting edge of the blade; that is to say, the axis of rotation of the disks 15 will be out of parallel relation to the axis of rotation of the blade 9, 80 the beveled face of one disk 15 will be in contact with and rotated by one inclined side of the blade 9 and the beveled face of the other disk 15 will be in contact with and rotated by the other inclined side of the 85 blade. When the bracket 14 is moved to the position shown in Fig. 2, and the pressure of the hand of the workman presses the disks 15 against the blade 9, the disks will grind and sharpen the cutting edge of the 90 blade in the usual manner.

The upper and rearward cutting edge of the blade 9, above the base plate 2 is guarded by a flange 17 formed on the standard 3. It is, however, necessary that the forward cutting edge of the blade have no permanent guard adjacent thereto, as the space adjacent this portion of the blade must be clear to receive the sharpening device when it is moved into the operative position. I therefore provide a guard which is carried by and movable with the bracket 14. This guard comprises a bar 18, preferably straight, as shown, extending through an opening in the bracket 14 and being longitudinally adjustable therein. The bar or guard 18 is engaged by a set screw 19 in the bracket 14 and the set screw is adapted to secure the bar 18 to the bracket in different positions of adjustment.

When the bracket 14 is in the raised position, shown in Fig. 1, the bar or guard 18 is in substantially a vertical position in advance of and adjacent to that side of the forward cutting edge of the blade 9 which it is desired to guard; or, in other words, the bar 18 is in the operative or guarding position, guarding the cutting edge of the blade in the region where it is acted upon by the sharpening device. When the bracket 14 is lowered from the position shown in Fig. 1 to the position shown in Fig. 2, the guard 18 is moved, from its operative position shown in Fig. 1 to its inoperative position shown in Fig. 2, and the sharpening disks 15 are moved from their inoperative position shown in Fig. 1 to their operative position shown in Fig. 2. Consequently, when the sharpening disks 15 are returned to their normal or inoperative position, the 190

guard 18 will, at the same time and by the same operation, be returned to its operative or normal position.

To hold the bracket 14 firmly in its normal position, shown in Fig. 1, I provide the bracket with a latch 20 pivoted thereto, at 21 and having a notched end adapted to engage an upwardly extending projection 22 on a plate or bracket 23 secured to the bottom of the motor case 4. The latch 20 has an arm or thumb piece 23 which projects over the outer portion of one side of the bracket 14, as shown, and has interposed between it and the bracket 14 a spring 24 which forces the latch 20 into engagement with the projection 22. When it is desired to lower the bracket 14 to grind or sharpen the blade 9, it is merely necessary for the workman to grasp the bracket 14 with his thumb upon the arm 23 and lower the bracket. The pressure of the thumb upon the arm 23, instantly releases the latch 20 from the projection 22 and permits the lowering of the bracket. The latch 20 and projection 22 are suitably beveled so that the latch 20 will ride over the projection 22 and reengage itself therewith when the bracket 14 is raised.

The pivot stud 13 has a spring 30 surrounding the same which is arranged and connected to the stud 13 and bracket 14 in a manner to raise the bracket 14 from the position shown in Fig. 2 to the normal position shown in Fig. 1 when the bracket is released. This raising of the bracket 14 by the spring 30 will, of course, cause the latch 20 to automatically reengage itself with the projection 22.

In order to locate the bar or guard 18 as near as possible to the forward cutting edge of the blade 9 when the guard is in the operative position and yet permit the bar 18 to clear the clamping collar 8 of the blade 9 when the lower portion of the guard 18 is raised to the inoperative position, I arrange the pivot stud 13 of the bracket 14 on an angle with respect to the axis of rotation of the blade 9, as clearly shown in Fig. 4. The angle of the stud 13 is such that the lower portion of the guard 18 will swing outwardly from the blade 9 as the guard moves to the inoperative position.

The main body of the bar or guard 18 is made flat with its broad faces substantially parallel to the plane of the side face of the cutter so as to obstruct the workman's view of the cutting line marked on the cloth, as little as possible; and in order to enable the workman to clearly see this cutting line, which is sometimes indistinctly marked and irregular, I provide a magnifying glass 25 so located as to permit the workman to readily see the cutting line through the glass as the line approaches the blade 9 during the cutting operation.

The glass 25 is mounted in a frame 26 having a collar 27 formed thereon which surrounds the round offset lower end of the guard 18 and is secured thereto by means of a suitable set screw 28. By loosening the set screw 28 the collar 27 and glass 25 may be adjusted, within limits, circularly about the axis of the offset lower end of the guard 18; and by loosening the set screw 19 and raising and lowering the guard 18, the glass 25 may be adjusted vertically. It will be observed that the glass 25 and its supporting parts are located to clear the blade 9 and its clamping collar 8 when the guard 18 is moved to the inoperative position, and that the movement of the guard 18 into and out of its operative position will also move the glass 25 into and out of its operative position.

Having thus described my invention, I claim.

1. In a cloth cutting machine the combination with a carriage, a circular blade rotatably mounted thereon, a bracket pivotally mounted on the carriage to have a swinging movement in a vertical arc; a grinding device and a guard device, for the blade, both mounted on said pivoted bracket, and a lever including a latch device adapted to actuate said pivoted bracket on its downward movement, and automatically lock it at the terminus of its upward movement.

2. In a cloth cutting machine comprising a movable carriage, a rotatable circular blade, a bracket pivoted on the carriage to have a swinging movement in a vertical arc, a grinding device, and a guard device, both mounted on said bracket in such relation to each other that the grinding device will be out of operative position when the guard is in operative position, and a latch adapted to automatically lock said elements in said positions.

3. In a cloth cutting machine comprising a movable carriage, a circular blade mounted rotatably thereon, a bracket pivotally mounted on the carriage to have a vertical swinging movement in an arc in front of the blade, means operating as a lever to depress said bracket and as a latch to automatically lock it in raised position, resilient means operating to raise said bracket into position to be locked, a grinding device and a guard bar, both directly mounted on said swinging bracket, whereby the guard bar is brought into and held in operative perpendicular position when the grinding device is raised into inoperative position.

4. In a cloth cutting machine comprising a movable carriage and a circular blade mounted thereon to be revoluble in a vertical plane, the combination therewith of a single movable bracket pivotally mounted on the carriage in such manner as to permit its arc-like reciprocation in front of and in

alinement with the plane of rotation of the revoluble cutting blade; a guard device, and a grinding device, both directly mounted on said bracket and actuated thereby in such 5 relation to each other that the guard device will be in operative position when the grinding device is out of operative position and vice versa, with devices adapted to impart the specified operative movement to said 10 bracket, substantially as set forth.

5. In a cloth cutting machine the combination with a carriage, a circular blade mounted rotatably thereon, a bracket pivotally mounted on the carriage and adapted 15 to have a swinging movement in a vertical arc, the axis of the pivot being disposed at an angle to the axis of rotation of the blade, a straight guard bar mounted directly on said bracket in such manner as to assume a 20 perpendicular position in front of the blade when the pivoted bracket is depressed, and to assume a position across the face of the blade when the pivoted bracket is raised; resilient means to automatically retract the 25 bracket when manually released from its lowered position, and means to automatically engage and lock it when it reaches the terminus of its upward position.

6. In a cloth cutting machine comprising 30 in combination a movable carriage and a

rotatable circular blade, a slotted bracket pivoted on the carriage and having a swinging movement in a vertical arc, a grinding device on said bracket, and a straight guard bar mounted longitudinally adjustable in the 35 slot of said bracket and in such relation thereto that it can only be brought into operative perpendicularity at the terminus of the upward swing of said bracket.

7. In a cloth cutting machine in combination with the movable carriage, a blade revoluble in a vertical plane, a bracket pivoted on the carriage and having a swinging movement in a vertical arc in a direction in front of the blade edge, of a straight 45 guard bar mounted on said bracket in such relation thereto as to be perpendicular in normal and operative position, said bar having its lower end constructed to support a transversely disposed magnifying lens and 50 provide a bearing therefor adapted to permit of its rotatable adjustment relatively to the blade edge.

In testimony whereof I have hereunto affixed my signature this 19 day of December 55 A. D. 1913.

MAYER R. MAIMIN.
